UNITED STATES PATENT OFFICE

118,614

DESIGN FOR A BREAD TUBE FOR RECEIVING A SAUSAGE OR THE LIKE

Moses A. Brin, Chicago, Ill.

Application November 28, 1939, Serial No. 88,528

Term of patent 7 years

To all whom it may concern:

Be it known that I, Moses A. Brin, a citizen of the United States of America and a resident of the city of Chicago, in the county of Cook and State of Illinois, have invented a new, original, and ornamental Design for a Bread Tube for Receiving a Sausage or the like, of which the following is a specification, reference being had to the accompanying drawing, forming part thereof.

The figure is a perspective view of a bread tube, showing my new design, the opposite side of the bread tube being the same as the side shown.

I claim:

The ornamental design for a bread tube for receiving a sausage or the like, as shown and described.

MOSES A. BRIN.
